E. L. SMITH

DOLL

Filed June 28, 1922

FIG. 1.

FIG. 2.

Inventor

Ella L. Smith,

By William L. Symons

her Attorney

FIG. 3.

UNITED STATES PATENT OFFICE.

ELLA L. SMITH, OF ROANOKE, ALABAMA.

DOLL.

Application filed June 28, 1922. Serial No. 571,407.

To all whom it may concern:

Be it known that I, ELLA L. SMITH, a citizen of the United States of America, residing at Roanoke, in the county of Randolph and State of Alabama, have invented certain new and useful Improvements in Dolls, of which the following is a specification.

My invention relates to dolls, and particularly to sanitary coverings for dolls.

The objects of my invention are: to provide a covering which may be readily removed from the doll, cleaned, and replaced on the doll body; to construct a covering of a small number of pieces of material which will conform to the body of the doll and which is easy and inexpensive to manufacture; to paint or otherwise form on the covering the features of a doll and to indicate parts of doll clothing; and to so construct the covering that ears are provided thereon which fit over ears provided on doll bodies.

With these and other objects in view, one embodiment of my invention is shown in the attached drawings, in which:

Figure 1 is a front view of the doll covering as applied to a doll;

Figure 2 is a rear view thereof; and

Figure 3 is a section on the line 3—3 of Figure 1.

My improved covering which may be made of any suitable material, such as stockinet, and which may be of any desired color or colors consists of a front piece 1, a back piece 2, and arm pieces 3 and 4, each made of a single piece of material. The front and back pieces are attached together as by sewing as indicated at 5, leaving no openings except for the arms and the opening in the back by means of which the covering is put on and taken off the doll body. The arm pieces are stitched on the lines 6 and 7 and are attached to the body covering in any suitable way, as by sewing, at the points indicated; for the arm piece 3, by 6^a and for the arm piece 4, by 7^a.

The neck may be made to conform to the slender neck of the doll by means of a dart seam 8, or by suitably drawing the material together. The opening 9 in the back, which opening is of sufficient length to allow the covering to be placed over the doll body, is closed by any suitable means, such as snaps 10.

The hair, eye-brows, eyes, lashes, nose, mouth, and cheeks may be indicated by painting the various parts a color in contrast with the color of the other parts of the covering, these parts being referred to by 11. Fingers may be indicated by painting, as shown at 12, while socks or stockings 13 may be indicated in like manner.

Ear coverings 14 cover the ears integral with or attached to the body and are rendered shapely and caused to remain in a distinctive position by the stitching 14^a.

It will be apparent from the description that by opening the snaps 10 the covering may be removed from the body, suitably cleaned, and returned thereto. My invention enables the child to have a series of coverings for the same doll body.

Having described my invention, what I claim and desire to secure by Letters Patent is:

A covering for a doll body comprising a front piece, a back piece, said back piece having an opening therein, means attached to said back piece for closing said opening, arm coverings each consisting of a single piece of material attached to said front and back pieces, and ear coverings formed by attaching the front and back pieces together by stitches placed adjacent the edges of said ear coverings whereby the ear coverings are adapted to fit over ears on the doll body and whereby the ear coverings are rendered distinctive and said cover being formed to conform to the neck portion of a doll body by inserting a dart in said front piece.

In testimony whereof I affix my signature.

ELLA L. SMITH.
